PAPER CARTON FOLDING APPARATUS

Albert Reisman, Philadelphia, Pa., assignor to J. Reisman & Sons, Inc., Pennsauken, N.J., a corporation of Pennsylvania

Filed Apr. 27, 1961, Ser. No. 106,057

2 Claims. (Cl. 93—49)

This invention relates to paper carton folding apparatus, and more particularly, to an apparatus for automatically manipulating a partition wall in a carton prior to the step of filling the carton with material.

Heretofore, it has been conventional in the art to manually place a partition wall in a carton designed to have a plurality of goods separated from one another by a partition. The manual positioning of such a partition wall is time consuming, expensive, and affects the production rate of filling cartons which material. I have discovered that the use of separate partitions can be eliminated by making a partition integral at one end with a side wall of the carton. The present invention is directed to an apparatus which automatically manipulates the partition wall out of the plane of the side wall of the carton and locates the same in a position extending between the side walls of the carton.

It is an object of the present invention to provide a novel apparatus which eliminates the necessity for manually placing partition walls in a carton.

It is another object of the present invention to provide a novel apparatus for manipulating a partition wall out of the plane of a side wall of a carton and disposing the same in a position extending between the side walls of the carton.

It is another object of the present invention to provide a novel apparatus which is capable of cooperating with cartons as they proceed along a conveyor belt so as to automatically provide the cartons with a partition wall.

It is still another object of the present invention to provide an apparatus which is simple and economical while capable of materially reducing the cost of a partition wall for a carton and materially increasing the rate at which such cartons may be filled with material.

Other objects will appear hereinafter.

For the purpose of illustrating the invention there is shown in the drawings a form which is presently preferred; it being understood, however, that this invention is not limited to the precise arrangements and instrumentalities shown.

FIGURE 1 is a partial perspective view of a box folding apparatus containing the present invention.

FIGURE 2 is an elevational view of the rotatable shaft and finger of the present invention.

FIGURE 3 is a partial plan view showing the structural interrelationship between the manipulating finger of the present invention and one position of a carton being conveyed past the finger.

FIGURE 4 is a partial plan view similar to FIGURE 3 showing another position of the carton and the manner in which the finger cooperates therewith.

FIGURE 5 is a partial plan view similar to FIGURES 3 and 4 showing another position of the carton and the manner in which the finger cooperates therewith.

FIGURE 6 is a perspective view of the carton adapted to cooperate with the finger as shown in FIGURES 3-5.

Referring to the drawing in detail, wherein like numerals indicate like elements, there is shown in FIGURE 1 a carton folding apparatus designated generally as 10.

The apparatus 10 includes a housing 12 within which is disposed means for folding blanks into a carton of the type shown in FIGURE 6. Such means forms no part of the present invention and therefore need not be shown or described in detail.

The housing 12 is provided with an outlet aperture 14

2

in an end wall thereof. A conveyor means is provided in the housing 12 between upright guide plates 16 and 18 mounted on a floor plate 19. The conveyor means includes runner plates 20 and 22 between which is disposed an endless chain 24. The endless chain 24 extends around a sprocket 25 rotatably supported below the floor plate 19. Cartons folded by the folding means within the housing 12 are conveyed between the guide plates 16 and 18 toward the aperture 14 by frictional engagement between the bottom wall on the carton and the chain 24.

5 A means 26 is provided for manipulating a partition wall on the carton just prior to the discharge of the carton through the outlet aperture 14. As shown more clearly in FIGURE 2, such means includes a C-shaped bearing block 28 fixedly secured to the upper surface of the floor plate 19. The bearing block 28 is provided with aligned apertures 30 and 32 in its horizontally disposed arms. An upright shaft 34 is rotatably supported within the apertures 30 and 32.

15 20 A finger 36 is adjustably secured to the shaft 34 at a point intermediate the arms on the C-shaped bearing block 28. As shown more clearly in FIGURES 3-5, the end of the finger 36 remote from the shaft 34 is semi-circular in plan view. The finger 36 extends through an 25 aperture 38 in the guide plate 16.

The uppermost end of the shaft 34 is provided with external threads 40. A lock nut 42 is threadingly engaged with the threads 40. A torsion spring 44 extends between the bearing block 28 and the lock nut 42. As 30 shown more clearly in FIGURE 2, one end of the spring 44 is fixedly secured to the lock nut 42 and the other end of the spring 44 is fixedly secured to the bearing block 28.

The carton with which the finger 36 is adapted to operate is shown more clearly in FIGURE 6 and is designated generally as 46. A side wall of the carton 46 is provided with a U-shaped slit. A score line 50 extends across the free ends of the U-shaped slit at a point equidistant from the ends of the carton 46.

35 40 The remaining elements not yet specifically described are more conveniently explained in conjunction with the manner in which the present invention is utilized.

As the cartons 46 are folded by a folding means within the housing 12, such cartons are conveyed to the outlet aperture 14 between the guide plates 16 and 18 by the chain 24. Suitable positioning means (not shown) may be provided to assure that the cartons 46 are juxtaposed to the guide plate 18 as shown more clearly in FIGURE 3. As the carton 46 approaches the end of the guide plates 16 and 18, the finger 36 is in the position shown in FIGURE 3.

45 50 55 As the carton 46 passes by the finger 36, the rounded end of the finger 36 presses against the side wall 51 of the carton 46. Since the side wall 51 is provided with a U-shaped slit, the finger 36 readily pushes the partition wall 48 inwardly as shown more clearly in FIGURE 4. As the partition wall 48 is moved to the position shown in FIGURE 4, the partition wall 48 pivots about the score line 50.

60 65 70 As the carton 46 continues in its movement past the finger 36, the portion of the wall 51 adjacent the score line 50 contacts the finger and rotates the same against the bias of the spring 44. That is, the finger 36 rotates in a clockwise direction in FIGURES 4 and 5 until the finger assumes the position shown in FIGURE 5. It will be understood that the spring 44 is weak enough so that the wall 51 adjacent the score line 50 is not torn by contact with the finger 36.

As the carton 46 continues to move under the influence of the chain 24, the rounded end of the finger 36 presses against the side wall 51 until the finger 36 clears the end 52 of the carton 46. Thereafter, the finger 36 rotates in

a counter clockwise direction to the position shown in FIGURE 3 due to the bias of the torsion spring 44.

As shown more clearly in FIGURES 4 and 5, the movement of the partition wall 48 out of the plane of the side wall 51 results in the provision of a rectangular aperture 54 having dimensions corresponding with the dimensions of the partition wall 48. It will be noted that the length of the partition wall 48 corresponds to the distance between the side walls of the carton 46. Sufficient details of the box 46 have been disclosed so as to understand the present invention. A more detailed disclosure of the carton 46 is not presented since the same forms a basis for a separate patent application.

It will be noted that the runner plates 20 and 22 extend beyond the end wall of the housing 12. As the cartons 46 pass out of the influence of the chain 24, the cartons 46 are deposited on an endless belt 56 having guide plates 58 and 60 extending therealong. The endless belt 56 conveys the cartons 46 in the direction of the arrow 62 which is perpendicular to the direction in which the cartons 46 were moving when under the influence of the chain 24. As the cartons 46 are conveyed in the direction of the arrows 62 by the endless belt 56, material such as pretzels are disposed on each side of the partition wall 48. Thus, the cartons 46 arrive at the station where they are filled with material with the partition wall 48 automatically disposed as shown in FIGURE 5. Therefore, the cost and necessity for separate manually insertable partition walls have been eliminated while increasing the production rate at which the cartons may be filled.

It will be understood that the cartons 46 are made from a semi-stiff paper and that the blanks for the cartons 46 are provided with the U-shaped slit and the score line 50. It will be obvious that the finger 36 lies in the same plane

as the partition wall 48. As shown more clearly in FIGURE 2, the vertical disposition of the finger 36 may be adjusted so as to accommodate different sized cartons and/or locations of the partition wall 48.

The present invention may be embodied in other specific forms without departing from the spirit or essential attributes thereof and, accordingly, reference should be made to the appended claims, rather than to the foregoing specification as indicating the scope of the invention.

I claim:

1. A carton folding apparatus comprising a conveyor means for conveying assembled cartons, guide plates on opposite sides of said conveyor means, a rotatable shaft mounted adjacent to one of said guide plates, said one guide plate having an aperture therethrough, a finger extending from said shaft through said aperture to a point where the end of said finger is capable of engaging a side wall of a carton moving past said shaft under the influence of said conveyor means, and spring means biasing said shaft to a position where said finger is juxtaposed to an edge of said aperture, with the extent of rotation of said shaft and finger being limited by the length of said aperture.

2. A carton folding apparatus in accordance with claim 1 wherein said spring means is a torsion spring surrounding said shaft, and means interconnecting said finger and said shaft so that the position of said finger along said shaft is selectively positionable.
